UNITED STATES PATENT OFFICE.

SAMUEL S. MATTHES, OF MANSFIELD, OHIO, ASSIGNOR TO THE OHIO BRASS COMPANY,
OF MANSFIELD, OHIO, A CORPORATION OF NEW JERSEY.

TROLLEY-ALIGNING HARP.

1,423,575.

Specification of Letters Patent. Patented July 25, 1922.

Application filed September 3, 1921. Serial No. 493,228.

To all whom it may concern:

Be it known that I, SAMUEL S. MATTHES, a citizen of the United States of America, residing at Mansfield, in the county of Rich-
5 land and State of Ohio, have invented cer-
tain new and useful Improvements in Trol-
ley-Aligning Harps, of which the follow-
ing is a specification.

My invention relates to an electric cur-
10 rent collector and has particular application
to so-called aligning harps in which it is
desired to maintain the collecting element
under normal conditions in alinement with
the axis of the pole.

15 In the drawings accompanying this speci-
fication:—

Fig. 1 shows a side view of my inven-
tion.

20 Fig. 2 shows a front end view of my
invention.

Fig. 3 shows a sectional view of the
aligning elements on the line 3—3 of Fig. 1.

25 Fig. 4 shows a sectional view of the align-
ing parts on the line A—A Fig. 2 when the
collector wheel is turned out of alinement
in the direction L.

Fig. 5 shows a sectional view of the align-
ing parts on the line A—A Fig. 2 when the
20 collector wheel and parts are in normal
aligned position.

Fig. 6 shows a sectional view of the align-
ing parts on the line A—A Fig. 2 when the
collector wheel is turned out of alinement in
the direction R.

35 In my preferred construction I provide
a body member 1 having a socket 2 to re-
ceive a pole as is the usual construction.
Secured to the body member is a table 3 and a
barrel 4. The barrel is provided with
40 a channel 5 having an enlarged chamber 6.
Within the chamber 6 is a rib 7 shown as
integral with the wall of the chamber. The
lower end of the chamber is open.

The harp 8 is arranged to receive a wheel
45 9 mounted on a spindle 10. Secured to the
lower part of the harp is a stem 11 arranged
to rotate with the harp and located in and
extending through the chambers 5 and 6. To
the lower end of the stem 11 is secured an
50 eye member 12 attached by means of screw
threads, pin, etc., and which maintains the
parts in assembled relation and to which
a rope may be attached for placing the de-
vice on a trolley wire from the ground.

55 The self aligning mechanism comprises

a sleeve 13 secured to and rotating with the
harp 8 and stem 11 by means of the key 14
engaging with the slot in the stem 11. At
each end of the sleeve 13 are slots 15 and
15' extending part way around the sleeve in 60
opposite directions from a common line.
Mounted on the stem 11 above and below
the sleeve 13 and free to rotate relative to
and slide longitudinal of the stem are col-
lars 16 and 16'. The collars are provided 65
with knobs 17 and 17' projecting into the
slots 15 and 15' respectively and arranged
to normally engage with one wall of the
slot as shown in Fig. 5. Each collar is also
provided with a stop 18 and 18' respectively 70
which normally engage the rib 7, one on
each side of the rib and holds the collars
against rotation in one direction. The
spring 19 has its ends engaging the knobs
17 and 17' under torsional stress which 75
tends to hold the stops 18 and 18' on the
collars normally against the rib 7 and
against rotation in one direction but per-
mits rotation of each collar in the oppo-
site direction. The spring also pressing up-
80 wardly and downwardly on the parts
16—16' tends to hold the harp 8 against the
table 3 for obvious electrical reasons.

The operation of my invention is as fol-
lows:—Referring to Fig. 5 the parts are 85
shown in normal alined position with the
wheel in line with the pole 20. The stops
18—18' on the collars 16 and 16' respec-
tively are in engagement with the rib 7
under tension of the spring 19 and the knobs 90
17 and 17' are in engagement with the end
walls of the slots 15 and 15' respectively on
the collar 13 thus holding the collar and
sleeve 11 which are keyed together in a nor-
mal alined position. 95

If the wheel is rotated in the direction
L, the harp and stud will rotate likewise and
also the sleeve 13 which in turn will rotate
the collar 16 through the medium of the
knob 17, (see Fig. 4) and the spring will 100
tend to rotate likewise on account of its
upper end engaging the knob 17, but since
the collar 16' cannot rotate on account of the
engagement of the stop 18' with the rib 7,
the lower end of spring 19 cannot rotate and 105
hence the torsional stress in the spring will
be increased, tending to rotate the collar
16, sleeve 13, stud 11, harp and wheel back
to normal.

When the wheel is rotated in the direc- 110

tion R, the function of the parts are reversed from that described above and as shown in Fig. 6 and the parts will be rotated back to normal alinement when the pressure

5 rotating the wheel in the direction R is released.

Having illustrated and described my invention, I claim—

1. An aligning collector comprising a body member provided with a recess and chamber, a harp comprising a pair of projecting arms to receive a contactor and a projecting stem to rotate with the harp and extending into and through the recess and chamber, a rib in the chamber, a sleeve mounted on the stem and within the chamber and arranged to rotate with the stem and having a shoulder at each end oppositely disposed from a line parallel to the axis of the sleeve, a pair of collars mounted to rotate on the sleeve and within the chamber and disposed one at each end of the sleeve and each collar provided with a lug to engage the adjacent shoulder on the sleeve, 25 and a lug to engage the rib in the chamber to prevent rotation of each collar in one direction but such direction being opposite in the case of the two collars; a spring mounted in the chamber surrounding the sleeve and positioned between the collars and having the ends bear one against each of the first mentioned lugs on the collars to rotate the collars in opposite direction and the second named lugs on the collars 30 into engagement with the rib to align the harp and simultaneously acting to spread the collars apart, and a member on the lower end of the stem to prevent the separation of the collars, and maintain the parts 35 in proper relation and against separation.

2. An aligning collector comprising a body member for attachment to a support, a member comprising means for mounting a collector and a stem for mounting the member on the body, means on the stem to rotate therewith to engage means rotatably mounted on the stem when the stem is rotated in one direction and to engage other means rotatably mounted on the stem when 45 the stem is rotated in the other direction, and stop means to prevent the rotation of each of the two rotatable means in one but opposite direction and yielding means engaging the two rotatable means acting to rotate them in opposite direction.

3. An aligning collector comprising a body member for attachment to a support, a member provided with a stem non-rotatably secured to the member and rotatably mounted in relation to the body, a helical spring surrounding the stem, and means rotatably mounted on the stem and engaging one end of the spring tending to tension the spring when the stem is rotated in one direction to increase its torsional strain and

means to engage the other end of the spring to prevent its rotation, all tending to maintain the stem and attached member in normal position.

4. An aligning collector comprising a body member for attachment to a support, a member provided with a stem arranged to rotate with the member and rotatably mounted in relation to the body, a helical spring surrounding the stem, means rotatably mounted on the stem and engaging one end of the spring tending to increase the torsional strain of the spring when the stem is rotated in one direction, means engaging the other end of the spring to hold it against rotation, means rotatably mounted on the stem to engage the last mentioned spring end to increase the torsional strain in the spring when the stem is rotated in the other direction, means to engage the first mentioned spring end to prevent its rotation by the last mentioned means, and means mounted on the stem to engage the rotatable means to move them alternately in opposite directions.

5. An aligning device comprising a body member for attachment to a support, a member provided with a collector and a stem to rotate with the member and rotatably mounted in relation to the body member, a coil spring surrounding the stem, mechanism acting to rotate one end of the spring in one direction to increase its torsional strain, and to prevent the rotation of the spring end in the other direction when the stem is rotated in the other direction, and mechanism acting on the other end of the spring simultaneously and in like manner as on the above mechanism but in reverse order of operation.

6. An aligning collector comprising a body member for attachment to a support, a member provided with a collector and a stem to rotate with the member and rotatably mounted in relation to the body member and mechanism tending to maintain the member in a normal or predetermined alined relation with the body member at all times but permitting the member to rotate to either side of the normal under stress, said mechanism comprising a resilient member under torsional strain and means rotatably mounted on the stem and acting on one end of the resilient member to increase the torsional strain when the stem and attached member are rotated in one direction and means rotatably mounted on the stem and acting on the other end of the resilient member to increase the torsional strain when the stem and attached member are rotated in the opposite direction.

7. An aligning collector comprising a body member for attachment to a support, a member provided with a collector and a stem to rotate with the member and rotatably mounted in relation to the body member and

mechanism for normally maintaining the harp in a predetermined alined position but permitting rotation in either direction from the normal under stress, said mechanism 5 comprising a resilient means having one end held against rotation in one direction and the other end held against rotation in the other direction when the stem and attached member are rotated in the above mentioned 10 directions respectively, said rotation in either direction increasing the strain in the resilient means and tending to rotate the stem and attached member back to normal when stress tending to rotate the stem and 15 member from normal is removed.

8. An aligning collector comprising a body member for attachment to a support, a member provided with a collector and a stem to rotate with the harp and rotatably 20 mounted in relation to the body member and mechanism for yieldingly holding the stem and member in a normal or alined position comprising resilient means under strain to normally maintain the stem and member in 25 alined position, means slidably mounted on the stem acting on one end of the resilient means to increase the strain therein and means acting on the other end to increase the tension therein when the stem and member 30 are rotated in opposite directions thereby returning the member to normal position.

9. An aligning collector comprising a body member for attachment to a support, 35 a member provided with a collector and a stem to rotate with the member and rotatably mounted in relation to the body, a spring having both ends acting upon the stem to maintain the stem and member in a normally 40 alined position, means rotatably mounted on the stem to act on one end of the spring to increase the tension in the spring when the stem and member are rotated in that direction and acting on the 45 other end of the spring to increase the tension therein when the stem and member are rotated in the other direction.

10. An aligning collector comprising a body member for attachment to a support, a 50 member provided with a collector and a stem to rotate with the member and rotatably mounted in relation to the body member and mechanism for yieldingly holding the stem and members in predetermined 55 alinement comprising a coiled spring, rotatable means mounted on the stem to rotate one end of the spring in one direction and to rotate the other end in the opposite direction and means interposed between said rotatable means on the stem and the body member to hold said rotatable means and each end of the spring against rotation in the direction opposite to rotation mentioned above.

65 11. An aligning collector comprising a

body member for attachment to a support, a member provided with a collector and a stem to rotate with the member and rotatably mounted to rotate relatively to the body member; mechanism for yieldingly holding the stem and member in predetermined alinement but permitting the stem and member to rotate in either direction from alinement comprising a coiled spring, means coacting with the coiled spring and the body and the stem whereby the torsional strain in the spring is increased when the stem is rotated in either direction under stress and whereby the stem is returned to its alined position when the stress is removed.

12. An aligning collector comprising a body member for attachment to a support, a member provided with a collector and a stem to rotate with the member and rotatably mounted in relation to the body member and mechanism for yieldingly holding the stem and member in predetermined alinement comprising a resilient member normally under tension and means coacting 90 with the resilient member and the stem and the body acting whereby the tension in the spring is increased when the stem is rotated in either direction and whereby the increased tension is made to react in the opposite direction to return the stem to its alined position.

13. An aligning device comprising a body member for attachment to a support, a member provided with a collector and a stem to 100 rotate with the member, a coiled spring having its ends arranged to rotate in opposite directions at alternate times when the stem is rotated in alternate directions, and means rotatably mounted on the stem to rotate the 105 opposite ends of the spring alternatively in opposite directions and hold the spring ends against rotation alternatively with the above rotations of the spring ends.

14. An aligning collector comprising a body member for attachment to a support, a member provided with a collector and securing means to rotate with the member and mounted in rotatable relation on the body member, a yielding member acting to maintain the member and body member in engagement and in a predetermined position of alinement relative to each other, and means interposed between each end of the yielding member and the member acting to 115 rotate one end of the yielding member in one direction and to rotate the other end of the yielding member in the other direction and to rotate the member back to normal under the stress of the yielding member.

15. An aligning device comprising a body member, a rotating member carried thereby and provided with a collector, a helical spring acting to maintain the body and rotating member in a predetermined alined 120 125 130

relation while permitting the parts to be moved out of alinement, means rotatably mounted on the rotating member and interposed between the spring and rotating member and means on the rotating member and coacting with the rotatably mounted means whereby the torsional strain in the spring is increased when the rotating member is moved in either direction from alinement thereby acting to move the parts back into alinement.

16. A current collecting device comprising a body member, a pivotally mounted member carried thereby and provided with a collecting member, and a helical spring acting to maintain the body member and the pivotally mounted member in a predetermined alined relation and simultaneously urging and maintaining the body and pivotally mounted member in engagement.

17. An aligning device comprising a body member, a pivotally mounted member carried thereby and provided with a stem and collecting member, a spring acting to maintain the body member and pivotally mounted member in a predetermined alined relation and having one end held against move-

ment in one direction, means rotatably mounted on the stem and engaging the other end of the spring acting to tension the spring when the stem is rotated and means to interlock the stem and rotatable means on the stem for coaction as described.

18. An aligning collector comprising a body member for attachment to a support, a member provided with a collector and a stem to rotate with the member and rotatably mounted in relation to the body member, and mechanism for yielding by holding the stem and member in predetermined alinement comprising a double acting spring, means rotatably mounted on the stem to engage each end of the spring and interlock with the body to prevent rotation of either spring end in one direction and the rotation of the other spring end in the opposite direction and means on the stem coacting with the rotatably mounted means thereon for transmitting motion to the stem from the spring and transmitting motion to the spring from the stem.

In testimony whereof I affix my signature.

SAMUEL S. MATTHES
